(57) **CLAIM**

The ornamental design for a light cover, as shown and described.

DESCRIPTION

FIG. 1 is a perspective view of the light cover;

FIG. 2 is a front elevation view thereof;

FIG. 3 is a rear elevation view thereof;

FIG. 4 is a right side elevation view thereof;

FIG. 5 is a left side elevation view thereof; and,

FIG. 6 is a top plan view thereof.

The broken lines in FIG. 3 indicate a thickness of the cover and the fact that the interior surface is not claimed.

The bottom of the light cover is unornamented, so that view is omitted.
